UNITED STATES PATENT OFFICE

109,697

DESIGN FOR A SNOW GUARD

Frank C. Cody, Chicago, Ill.

Application March 14, 1938, Serial No. 75,788

Term of patent 14 years

To all whom it may concern:

Be it known that I, Frank C. Cody, a citizen of the United States, residing at Chicago, in the county of Cook and State of Illinois, have invented a new, original, and ornamental Design for a Snow Guard, of which the following is a specification, reference being had to the accompanying drawing, forming part thereof.

I claim:

The ornamental design for a snow guard as shown.

FRANK C. CODY.
